HOLD-DOWN CLAMP

Max E. Wetzler, Long Island City, N. Y.

Application February 10, 1942, Serial No. 430,189

4 Claims.

(Cl. 90—59)

My invention relates to hold down clamps and more particularly to that type of hold down clamps which constitute attachments for drill presses, milling machines and other apparatus.

The invention has for its object the provision of a novel hold down clamp of the indicated type which may be readily and efficiently combined with the machines for which it is intended, and which is capable of being adjusted with a minimum of effort to effect its operative functions.

The invention contemplates further the provision of a novel hold down clamp in which the clamping instrumentalities are arranged to be adjusted to operative positions at high speed and in a minimum of time.

Other objects will appear from the description hereinafter and the features of novelty will be pointed out in the claims.

In the accompanying drawings, which illustrate examples of the invention without defining its limits,

Fig. 1 is a perspective view of the novel hold down clamp embodied in a conventional drill press;

Fig. 2 is a side elevation thereof with parts in section;

Fig. 3 is a plan view of the novel hold down clamp;

Fig. 4 is a detail view illustrating another form of attaching means whereby the hold down clamp may be combined with the table or bed-plate of another machine;

Fig. 5 is a side elevation partly broken away and in section, of another form of the novel hold down clamp;

Fig. 6 is a plan view thereof;

Fig. 7 is a side elevation partly broken away and in section of a further form of the novel hold down clamp, and

Fig. 8 is a plan view thereof.

As shown in Figs. 1, 2 and 3, the novel hold down clamp comprises a preferably circular base 10 of suitable dimensions and preferably constructed of metal or other suitable material. The base 10 carries an upright member 11 which in the form under discussion is of rectangular cross-section and projects upwardly from said base 10 as shown in Figs. 1 and 2. The upright member 11 may be fastened upon the base 10 in any convenient manner, for instance, as shown in the drawings by means of two lugs 12 which constitute integral parts of the base 10 and a rivet or equivalent fastening device 13 which extends transversely through the lugs 12 and upright member 11 to fix the latter in place on said base 10.

The hold down clamp further includes a clamping bracket 14 provided with an elongated rectangular slot 15 whereby said clamping bracket 14 is slidably mounted on the upright member

11. Preferably the one end wall of the slot 15 is inclined as indicated at 16 in Fig. 2 for the purpose to be more fully described hereinafter. The clamping bracket 14 is slidably mounted on the upright member 11 in transverse relation thereto and at its one end carries a clamping member 17 which is in swivelled connection therewith by means of a ball and socket connection 18 and depends from the clamping bracket 14 as illustrated in Fig. 2. The opposite end of the clamping bracket 14 includes an integral depending arm 19 in which a pressure developing spindle 20 is mounted in screwthreaded engagement therewith. A pressure member 21 is mounted upon the spindle 20 preferably by means of a ball and socket connection 22 so as to be in swivelled connection with said spindle 20 as shown in Fig. 2. To facilitate the operation of the spindle 20 and its associated parts, a manipulating device, for instance, in the form of a thumb nut 23, may be fixed on said spindle. The clamping bracket 14 further carries a fulcrum member 24 secured in place in any suitable manner and extending transversely across the slot 15 in engagement with one upright edge surface of the upright member 11.

Suitable means is provided for movably mounting the novel hold down clamp in an associate machine such as a drill press, a milling machine, or the like. In the form shown in Figs. 1 and 2, the aforesaid means is illustrated in a form designed for mounting the hold down clamp in machines in which the bed-plates of said machines are accessible from the bottom.

In the arrangement illustrated in Figs. 1 and 2, the novel hold down clamp is mounted upon the bed-plate or table 25 of a conventional drill press which bed-plate 25 is provided with a slot 26 in the conventional manner. The fastening means whereby the novel hold down clamp is movably mounted on said bed-plate or table 25 is illustrated in the form of a screw 27 passing loosely through a plate or washer 28 and provided with a manipulating device, for instance, in the form of a wing nut 29. In such case, the base 19 is provided with an internally screwthreaded opening for the threaded accommodation of the screw 27.

In practice the plate or washer 28 lies in surface engagement with the lower face of the table or bed-plate 25 so as to span the slot 26 thereof, and the screw 27 projects upwardly through said slot into threaded connection with the threaded opening of the base 10. As the screw 27 is screwed into said opening, the base 10 and the plate or washer 28 will be clamped upon opposite faces of the bed-plate or table 25 to securely fix the novel hold down clamp in the desired position in the drill press or other machine. It will be noted that the screw 27 may be shifted length-

wise of the slot 26 to vary the location of the hold down clamp upon the bed-plate or table 25.

In operation the work A is set in position upon the bed-plate or table 25 after which the clamping bracket 14 is moved downwardly upon the upright member 11 until the clamping member 17 comes into engagement with said work A. It will be understood that at this stage the pressure member 21 is in loose sliding engagement with the one upright edge surface of the upright member 11. When the clamping member 17 has reached the work A, the spindle 20 is manipulated by means of the device 23 or its equivalent to force the pressure member 21 against the upright edge of the upright member 11. As the spindle 20 is thus manipulated, the depending arm 19 of the clamping bracket 14 will be forced away from the upright member 11 to thereby force the fulcrum member 24 against the contiguous upright edge surface of the upright member 11 as will be obvious. Continued operation of the spindle 20 in the indicated manner will bring about a rocking movement of the clamping bracket 14 in a direction to force the clamping member 17 into clamping engagement with the work A to thereby firmly and securely clamp the latter in its intended position upon the bed-plate or table 25 for drilling by the conventional drill B or for treatment by other tools or devices.

When the particular operation on the work A has been completed, a reverse operation of the spindle 20 will quickly relieve the clamping pressure of the clamping member 17 on the work A and at the same time relieve the pressure of the pressure member 21 on the member 11 and correspondingly relieve the fulcrum member 24 from engagement with the opposite edge surface of the upright member 11 and thereby enable the clamping bracket 14 and its associated parts to be raised away from the work A and if desired to be completely removed from the upright member 11. In any case, the work A is freed for removal from the machine.

The hold down clamp may be speedily and easily brought into clamping engagement with the next successive work A by sliding the clamping bracket 14 downwardly upon the upright member 11 until the work A is engaged by the clamping member 17 and then repeating the operations hereinbefore described.

To enable the novel hold down clamp to be mounted in place upon the bed-plate or tables 25' of machines such as milling machines, the means exemplified in Fig. 4 may be provided. The bed-plates or tables 25' of milling machines and other machines are generally provided with slots 26' having under-cut portions 26a. For mounting upon such bed-plates 25' the base 10 is fixed upon a screw 27' having a circular head 29' and carrying a lock nut 27a and a washer 28'.

In practice the head 29' is inserted into the under-cut portion 26a of the slot 26' with the screw 27' projecting upwardly through the slot 26' and with the washer 28' resting upon the upper surface of the bed-plate or table 25' as shown in Fig. 4. The novel hold-down clamp may be fixed upon the bed-plate or table 25' at any point in the slot 26' by simply screwing the nut 27a downwardly upon the screw 27' to force the head 29' of the screw 27' and the washer 28' into clamping engagement with the surface of the under-cut portion 26a of the slot 26' and the upper surface of the bed-plate or table 25 respectively.

With the arrangement illustrated in Fig. 4, the

clamping bracket 14 may be swung to different operative positions on the axis of the screw 27' or to an inoperative position out of the way, by simply loosening the nut 27a to relieve the clamping pressure of the washer 28' and screw head 29'. The same result may be obtained with the form shown in Figs. 1 and 2 by loosening the screw 27, which operation is however sometimes difficult because of the relative inaccessibility of the manipulating device 29 beneath the bed-plate or table 25.

In the form shown in Figs. 5 and 6, the upright member 11' is mounted upon a base 10' so as to project upwardly therefrom and is of rectangular cross-section as in the form first described. The upright member 11' may be secured upon the base 10' in the same way as previously set forth herein and may differ from the upright member 11 only by being provided with a plurality of apertures 30 located in spaced relation lengthwise of said upright member 11' and extending transversely therethrough. In this form of the novel hold down clamp a fulcrum member 24' is carried by the clamping bracket 14' in the slot 15' thereof and is arranged to extend through a selected one of the apertures 30 to position the clamping bracket 14' on the upright member 11'. Otherwise this form of the novel hold down clamp may be constructed in the same way as set forth hereinbefore.

In practice the clamping bracket 14' is slidably adjusted lengthwise of the upright member 11' until the swivelled clamping member 17 comes into engagement with or in close proximity to the work A after which the fulcrum member 24' is inserted through the clamping bracket 14' and through the particular aperture 30 which happens to be in proper position to receive said fulcrum member 24'. The spindle 20 is then operated as in the previous form, to force the pressure member 21 against the upright member 11' and thereby force the depending member 19 of the clamping bracket 14' away from said upright member 11'. This causes the clamping bracket 14' to rock on the fulcrum member 24' and force the clamping member 17 into clamping engagement with the work A. The base 10' may be provided with either of the fastening means shown in Figs. 2 and 4 respectively for mounting this form of the vise in operative position in the machine.

The form of the novel hold down clamp shown in Figs. 7 and 8 comprises a base 10a similar to the previously mentioned bases 10 and 10' and supporting a member 11a in upright position as in the forms previously described. The upright member 11a is of cylindrical form and of any suitable dimensions dependent upon the specific functions to be performed by the novel hold down clamp of which it forms a part. A clamping bracket 14a corresponding generally in construction with the previously described clamping brackets is provided with an elongated slot 15a whereby the clamping bracket 14a is slidably mounted on the upright member 11a. Preferably the slot 15a is curved at its opposite ends and at one end is sloping as indicated at 16a for the purpose to be more fully described hereinafter. The clamping bracket 14a further carries a fulcrum member 24a located in the slot 15a and extending transversely across the same in tangential engagement with the surface of the upright member 11a as shown in Fig. 8. The clamping bracket 14a carries a swivel clamping member 17a corresponding to the previously mentioned clamping

member 17 and is further provided in its depending arm 19^a with a screwthreaded spindle 20^a having a manipulating device 23^a and a swivelled pressure member 21^a. The latter is preferably curved to fit the cylindrical surface of the upright member 11^a as shown in Fig. 8. The base 10^a may be provided with any suitable means such as shown for instance in Figs. 2 and 4 for mounting this particular form of the hold down clamp in a drill press, milling machine or any other machine in which it may be useful.

The form of the hold down clamp shown in Figs. 7 and 8 functions and operates in the same way as previously described herein. In this last-mentioned form of the novel hold down clamp the clamping bracket 14^a is capable of being swung on the axis of the upright member 11^a to various operative positions in the machine or to an inoperative position therein without in any way disturbing the means whereby the novel hold down clamp is mounted in the particular machine.

In all of its forms the inclined end walls 16 and 16^a of the respective slots 15, 15' and 15^a enable the respective clamping brackets to develop the necessary rocking movements relatively to the upright members to bring the clamping members 17 and 17^a into the most efficient clamping engagement with the particular work.

The novel hold down clamp regardless of its specific arrangement and construction is capable of being shifted into proper operative clamping relation with the work with maximum speed and without requiring any lengthy and tedious adjustments. The novel hold down clamp in addition to its other advantages serves to materially speed up the productive results of the respective machines with which said hold down clamp may be combined. In all of its forms the novel hold down clamp is simple in construction and requires no particular skill in its operation and setting in or combination with the machines for which it is designed.

Various changes in the specific forms shown and described may be made within the scope of the claims without departing from the spirit of the invention.

I claim:

1. A hold down clamp of the kind described comprising a base, an upright member fixed upon said base and projecting upwardly therefrom, a clamping bracket having a slot for slidably mounting said bracket on said upright member for adjustment lengthwise thereof, a swivelled clamping member carried by said clamping bracket for engagement with the work, a fulcrum member carried by said clamping bracket in the slot thereof and extending transversely of the upright member in engagement therewith, a pressure developing spindle carried by said clamping bracket in threaded engagement therewith, a pressure member in swivelled connection with said spindle for engagement with said upright member in opposed relation to said fulcrum member, said spindle co-operating with said fulcrum member to force said clamping member into clamping engagement with the work, and means whereby said base is adapted to be movably connected with the bed-plate of a machine to mount said hold down clamp in said machine.

2. A hold down clamp of the kind described

comprising a base, an upright member of rectangular cross-section fixed upon said base and projecting upwardly therefrom, a clamping bracket having an elongated rectangular slot for slidably mounting said bracket on said upright member for adjustment lengthwise thereof, a swivelled clamping member carried by said clamping bracket for engagement with the work, a fulcrum member carried by said clamping bracket in the slot thereof in engagement with an upright edge surface of said upright member, a pressure developing spindle carried by said clamping bracket in threaded engagement therewith, a pressure member in swivelled connection with said spindle for engagement with the opposite upright edge surface of said upright member, said spindle co-operating with said fulcrum member to force said clamping member into clamping engagement with the work, and means whereby said base is adapted to be movably connected with the bed-plate of a machine to mount said hold down clamp in said machine.

3. A hold down clamp of the kind described comprising a base, an upright member of rectangular cross-section fixed upon said base and projecting upwardly therefrom, said upright member being provided with a plurality of spaced apertures extending transversely therethrough, a clamping bracket having an elongated rectangular slot for slidably mounting said clamping bracket on said upright member for adjustment lengthwise thereof, a swivelled clamping member carried by said clamping bracket for engagement with the work, a fulcrum member carried by said clamping bracket in the slot thereof and extending through a selected one of the apertures of said upright member, a pressure developing spindle carried by said clamping bracket in threaded engagement therewith, a pressure member in swivelled connection with said spindle for engagement with an upright edge surface of said upright member, said spindle co-operating with said fulcrum member to force said clamping member into clamping engagement with the work, and means whereby said base is adapted to be movably connected with the bed-plate of a machine to mount said hold down clamp in said machine.

4. A hold down clamp of the kind described comprising a base, a cylindrical upright member fixed upon said base and projecting upwardly therefrom, a clamping bracket having an elongated slot for slidably mounting said clamping bracket on said upright member, a swivelled clamping member carried by said clamping bracket for engagement with the work, a fulcrum member carried by said clamping bracket in the slot thereof and extending transversely of the upright member in tangential engagement therewith, a pressure developing spindle carried by said clamping bracket in threaded engagement therewith, a pressure member in swivelled connection with said spindle and curved to fit said upright member in opposed relation to said fulcrum member, said spindle co-operating with said fulcrum member to force said clamping member into clamping engagement with the work, and means whereby said base is adapted to be movably connected with the bed-plate of a machine to mount said hold down clamp in the machine.

MAX E. WETZLER.
